UNITED STATES PATENT OFFICE.

ALCÉE CAILLOUETTE, OF CENTRAL, LOUISIANA, ASSIGNOR OF ONE-HALF TO JOSEPH CAILLOUETTE, JR., OF CENTRAL, LOUISIANA.

DEVICE FOR CONNECTING BLADES TO SNATHES.

1,130,666.

Specification of Letters Patent. Patented Mar. 2, 1915.

Application filed September 9, 1914. Serial No. 860,909.

To all whom it may concern:

Be it known that I, ALCÉE CAILLOUETTE, a citizen of the United States, residing at Central, in the parish of St. James and State of Louisiana, have invented new and useful Improvements in Devices for Connecting Blades to Snathes, of which the following is a specification.

This invention relates to briar hooks, scythes and like devices and more particularly to means for connecting the blades to the snathes or handles, the principal object of the invention being to effect a simple, efficient and adjustable connection whereby the blade may be placed at any angle to the snathe desired. In using implements of this character each operator has his own particular desire regarding the position of the blade with relation to the snathe and the range of adjustment heretofore provided on these devices has been so limited that the accommodation of many in this respect is out of the question. For this reason the present improvement has been devised and is so constructed that the blade may fold directly against the snathe or extend parallel with the same but project beyond the end thereof, thus giving a wide range of adjustment.

Further objects of the invention will appear as the following description is read in connection with the accompanying drawing, which forms a part of this application, and in which:

Figure 1 is a side elevation. Fig. 2 is a front elevation. Fig. 3 is a rear elevation. Fig. 4 is a detail plan view of the blade.

Referring more particularly to the drawing, 1 represents a briar hook blade which is sharpened upon both edges and has secured to its outer end a substantially triangular member 2, both side edges of which are sharpened as shown. To the rear end of the blade 1 there is permanently secured a plate 3 having its forward end upturned and curled into the form of a hinge knuckle 4 to receive the connecting and pivoting bolt 5

which joins the blade to the snathe 6. The bolt 5 passes through the extended ends of reinforcing plates 7 which are secured upon opposite sides of the snathe in any suitable manner as by bolts 8 or rivets 9. The rear end of the plate 3 is also curled into a hinge knuckle 10 through which the bolt 11 passes. This bolt also passes through the eyes formed at the lower ends of the right angular adjusting arms 12. These arms have their short legs apertured to receive the connecting and adjusting bolts 13 and 14 arranged upon opposite sides of the snathe and adapted to clamp the arms 12 against the plates 7 and when the arms 12 are firmly bound against the sides of the snathe the blade will be securely held in adjusted position.

Surrounding the snathe and held in position thereon by the clamping bolts 15 are the clamping and pivoting plates 16. These plates are arranged to receive the handle 17 between them which is slotted, as shown at 18, to receive one of the clamping bolts 15 so that it may have any desired amount of adjustment in either direction. By loosening the clamping plates the handle may be turned around on the snathe so as to secure it in adjusted position angularly with relation to the blade.

What is claimed is:

In a device of the class described, a snathe, a blade, a plate secured to the blade adjacent one end and having opposite ends curled into hinge knuckles, plates secured to opposite sides of the snathe and hingedly connected with the inner knuckle, arms hinged to the outer knuckle and arranged to straddle the plates, and bolts for binding the arms against said plates.

In testimony whereof I affix my signature in presence of two witnesses.

ALCÉE CAILLOUETTE.

Witnesses:

A. B. VIGES,
JOE JOURDAIN.
